UNITED STATES PATENT OFFICE

2,494,953

MOVING BULK MATERIALS

Denzil O. Martin, Banning, Calif., assignor, by
mesne assignments, to Robertson Engineering
Corporation, San Francisco, Calif., a corpora-
tion of California

Application September 17, 1946, Serial No. 697,545

14 Claims. (Cl. 214—44)

1

This invention relates to moving bulk materials, and more particularly for the transfer of bulk materials, such as grain, sand and the like from a bin to a suitable receptacle.

Another object is to facilitate the unloading of bulk materials from the interior of a box car, bin or similar receptacle in which such materials may be stored.

A further object is to avoid the dangers incident to the handling of bulk materials, by avoiding the necessity for having an attendant enter the bin or box car during the removal of the contents thereof.

Among its features, my invention embodies a boom adapted to extend across the open front of a bin or the like, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and guide pulley, and a drag bucket connected to the adjacent ends of the cables.

Other features include power means by which pull may be transmitted to the cables to cause the bucket to advance and retract within the bin, and power means to shift the bucket advancing and sustaining pulley longitudinally of the boom.

In the drawings,

Figure 1 is a top plan view of a material moving device embodying the features of this invention;

Figure 2 is a side view of the material moving equipment illustrated in Figure 1;

Figure 3 is an end view thereof;

Figure 4 is an enlarged fragmentary sectional view taken substantially along the line 4—4 of Figure 2, and

Figure 5 is an enlarged fragmentary sectional view taken substantially along the line 5—5 of Figure 2.

Referring to the drawings in detail, a base 10 is provided adjacent opposite side edges with upwardly extending columns 11, the upper ends of which incline inwardly as at 12 (Fig. 3), and terminate at their upper ends in spaced parallel supports 13 which are pierced to receive axially aligned bolts 14 upon which flanged wheels 15 are rotatably supported. The upper and lower ends of the spaced parallel extensions 13 are held in spaced parallel relation by transversely extending bridge plates 16 to form a pair of longitudinally spaced substantially boxlike structures in which the flanged wheels 15 rotate. As illustrated

in the drawings, the wheels 15 have their flanges turned outwardly so as to rotate adjacent the spaced upstanding members 13.

A boom designated generally 17 comprising a pair of spaced parallel channels 18, held in spaced parallel relation by cross braces 19 so that the flanges 20 of the channels 18 extend outwardly and ride on the wheels 15 previously referred to. Inasmuch as all the bolts 14 are in the same horizontal plane it will be obvious that the boom 17 may slide horizontally between the uprights 13 previously described.

Mounted for longitudinal sliding movement on the boom 17 is a carriage designated generally 21 which comprises a substantially U-shaped yoke 22, each leg of which is pierced to receive a bolt 23 which forms the axle about which a roller 24 rotates. Depending from the bight portion of the U-shaped yoke 22 is a pair of longitudinally spaced ears 25 which are pierced to receive a pivot pin 26, the purpose of which will be more fully hereinafter described. As illustrated in the drawings, the pivot pin 26 extends parallel with the longitudinal axis of the boom and supports for swinging movement through an arc of one hundred eighty degrees a depending yoke 27 in which is supported a bucket advancing and sustaining pulley 28. It will thus be seen that the pulley 28 is supported for movement longitudinally of the boom 17. A suitable attaching eye 29 is carried at one end of the carriage 21 and any suitable connecting member 30 is carried adjacent the opposite end of the carriage 21. The purpose of the eye and attaching member will be more fully hereinafter explained.

Extending upwardly from the boom 17 near its outer end is a pair of longitudinally spaced ears 30 supporting a pivot pin 31 which extends parallel to the longitudinal axis of the boom and pivotally supports a yoke 32 in which a bucket retracting pulley 33 is rotatably supported. As illustrated in Figure 5, this pulley is adapted to be rotated upwardly through an arc of one hundred eighty degrees so as to be operable from either side of the boom.

Mounted at the extreme outer end of the boom 17 for rotation about an axis extending transversely of the longitudinal axis of the boom is a pulley 34 over which a carriage advancing cable 35 is trained. One end of this cable is attached to the eye 26 of the carriage 21, while its opposite end is trained over an idler pulley 36 carried by the boom near its opposite end. This cable then extends downwardly and is adapted to be wound upon a winding drum 37 mounted for

rotation in suitable brackets 38 carried by the base 10. It will thus be seen that by winding the cable 35 on the drum 37 pull will be exerted on the carriage 21 to move it toward the free end of the boom in which the pulley 34 is mounted.

Extending transversely of the bin or body of a car which is to be unloaded is a trench jack 39 to which the yoke 40 of a guide pulley 41 is connected. This trench jack 39 is preferably firmly secured adjacent the back wall of the bin or car to be unloaded, and trained over the pulley 41 and the bucket retracting pulley 32 is a cable 42, one end of which is attached to the rear side of a drag bucket 43, while the opposite end of said cable is trained over an idler pulley 44 and thence downwardly to be wound upon a winding drum 45. The drum 45 is mounted to rotate in a suitable bracket 46 carried by the base 10 and it will be seen that when the cable 42 is wound thereon, pull will be exerted on the bucket 43 to move it toward the back of the bin or car in which the device is being used.

A bucket advancing cable 47 is attached to the bail 48 of the drag bucket 43 and is trained over the pulley 27 from whence it passes longitudinally along the underside of the boom to an idler pulley 49 mounted between the standards 11 at the forward end of the base 10. The cable 47 then passes downwardly to a winding drum 50 mounted for rotation in a pair of spaced brackets 51 carried by the base 10. It will thus be seen that when the cable 47 is wound upon the drum 50 the drag bucket 43 will be moved toward the boom and away from the back wall of the bin or car.

A prime mover 52 is mounted on the base 10 and has driving connection with a gear train 53 through the medium of a drive belt 54. The gear train is connected through a series of clutches to the drive shafts of the drums 37, 45 and 50 controlled respectively by clutch levers 55, 56 and 57 by which the clutches selectively may be actuated to drive their respective winding drums. It will thus be seen that by manipulating the clutch levers the drums may selectively be set into operation.

In use, the trench jack 39 is first adjusted snugly to fit between the side walls of the bin or car to be unloaded and the guide pulley 41 is thus anchored in proper position to perform its function. The boom 17 is then moved outwardly so that it extends transversely across the open front side of the bin in which the material to be unloaded is confined. The lever 55 is then manipulated to set the drum 37 in operation to wind the cable 35 thereon and hence move the carriage 21 to the desired position in front of the bin. Having thus positioned the carriage and the bucket advancing and sustaining roller 27 to its proper place in front of the bin, the hand lever 56 is manipulated to cause the drum 45 to be driven so as to wind the cable 42 thereon. The taking up of the cable 42 causes the bucket 43 to be moved toward the rear wall of the bin over the material contained therein, and when the bucket has been moved to a point near the rear wall of the bin or car, rotation of the drum 45 is stopped and the lever 57 is then manipulated to set the drum 50 into motion to wind the cable 47 thereon and cause the bucket 43 to scrape the contents of the bin toward the front thereof, simultaneously filling the bucket. Upon continued operation of the drum 50 it is obvious that the bucket will be drawn upwardly to be suspended from the pulley 28, and continued pull after the elevation of the bucket will cause the carriage 21 to move longitudinally

of the boom 17 and toward the standards 11. When the bucket has achieved the desired position its contents may be discharged and the operation repeated until the entire contents of the bin has been removed.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables.
2. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables.
3. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, and means to shift the bucket advancing and sustaining pulley longitudinally of the boom.
4. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, and power driven drums upon which the opposite ends of the cables are adapted to be wound.
5. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, and power driven drums upon which the opposite ends of the cables are adapted to be wound.
6. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, and power driven drums upon which the opposite ends of the cables are adapted to be wound.
7. A device for moving bulk materials from a bin or the like having side walls, a back wall and an open front, which includes, a boom mounted to move in a rectilinear path into a position to extend across the open front of the bin in spaced parallel relation to and above the plane of the bottom thereof, a bucket advancing and sustaining pulley movable longitudinally of the boom, a bucket retracting pulley on the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, and power driven drums upon which the opposite ends of the cables are adapted to be wound.

fear end, a bucket advancing and sustaining cable extending around the bucket advancing and sustaining pulley, a bucket retracting cable extending around the bucket retracting pulley and the guide pulley and a drag bucket connected to the adjacent ends of the cables, and means to shift the bucket advancing and sustaining pulley longitudinally of the boom, and power driven drums upon which the opposite ends of the cables are adapted to be wound.

5. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables.

6. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables, and means to shift the carriage longitudinally of the boom.

7. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables, and power driven drums upon which the opposite ends of the cables are adapted to be wound.

8. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining

pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables, and means to shift the carriage longitudinally of the boom, and power driven drums upon which the opposite ends of the cables are adapted to be wound.

1 A device for moving bulk materials from a
15 bin or the like having side walls, a back wall and
an open front, which includes, a boom mounted
to move in a rectilinear path into a position to
extend across the open front of the bin in spaced
parallel relation to and above the plane of the
20 bottom thereof, a bucket advancing and sustaining
pulley movable longitudinally of the boom,
a bucket retracting pulley on the boom, a guide
pulley adapted to be fixed in the bin near its
rear end, a bucket advancing and sustaining cable
25 extending around the bucket advancing and sus-
taining pulley, a bucket retracting cable extend-
ing around the bucket retracting pulley and the
guide pulley and a drag bucket connected to the
adjacent ends of the cables, and power driven
30 means selectively to exert pull on the opposite
ends of the cables.

10. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables, and power driven means selectively to exert pull on the opposite ends of the cables.

11. A device for moving bulk materials from a bin or the like having side walls, a back wall and an open front, which includes, a boom mounted 55 to move in a rectilinear path into a position to extend across the open front of the bin in spaced parallel relation to and above the plane of the bottom thereof, a bucket advancing and sustaining pulley movable longitudinally of the boom, a 60 bucket retracting pulley on the boom, a guide pulley adapted to be fixed in the bin near its rear end, a bucket advancing and sustaining cable extending around the bucket advancing and sustaining pulley, a bucket retracting cable extending 65 around the bucket retracting pulley and the guide pulley and a drag bucket connected to the adjacent ends of the cables, and power driven means to move the bucket advancing and sustaining pulley longitudinally of the boom.

70 12. A device for moving bulk materials from a bin or the like having side walls, a back wall and an open front, which includes a boom mounted to move in a rectilinear path into a position to extend across the open front of the bin in spaced 75 parallel relation to and above the plane of the

bottom thereof, a carriage movable longitudinally of the boom, a bucket advancing and sustaining pulley carried by the carriage, a bucket retracting pulley on the boom, a trench jack anchored transversely of the bin near its rear wall, a guide pulley carried by the trench jack, a bucket advancing and sustaining cable extending around the bucket advancing and sustaining pulley, a bucket retracting cable extending around the bucket retracting pulley and the guide pulley and a drag bucket connected to adjacent ends of the cables, and power driven means to move the carriage longitudinally of the boom.

13. A device for moving bulk materials from a bin or the like having side walls, a back wall and an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley pivotally supported on the carriage to swing about an axis parallel with the longitudinal axis of the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables.

14. A device for moving bulk materials from a bin or the like having side walls, a back wall and

an open front, which includes a boom mounted to move in a rectilinear path into a position to extend across the open front of the bin in spaced parallel relation to and above the plane of the bottom thereof, a carriage movable longitudinally of the boom, a bucket advancing and sustaining pulley pivotally supported on the carriage to swing about an axis parallel with the longitudinal axis of the boom, a guide pulley adapted to be fixed in the bin near its rear end, a bucket advancing and sustaining cable extending around the bucket advancing and sustaining pulley, a bucket retracting cable extending around the bucket retracting pulley and the guide pulley and a drag bucket connected to the adjacent ends of the cables, power driven means to move the carriage longitudinally of the boom and power driven drums upon which the opposite ends of the cables are adapted to be wound.
